(57) **CLAIM**

The ornamental design for a cup lid with a condiment holder, as shown and described.

DESCRIPTION

FIG. 1 is a top perspective view of a cup lid with a condiment holder, showing our new design;

FIG. 2 is a bottom perspective view of FIG. 1;

FIG. 3 is a top plan view of FIG. 1;

FIG. 4 is a bottom plan view of FIG. 1;

FIG. 5 is a cross-sectional view thereof, taken along line 5-5 of FIG. 3;

FIG. 6 is a cross-sectional view thereof, taken along line 6-6 of FIG. 3;

FIG. 7 is a cross-sectional view thereof, taken along line 7-7 of FIG. 3;

FIG. 8 is a cross-sectional view thereof, taken along line 8-8 of FIG. 3;

FIG. 9 is a cross-sectional view thereof, taken along line 9-9 of FIG. 3; and,

FIG. 10 is a cross-sectional view thereof, taken along line 10-10 of FIG. 3.

The broken lines in the figures depict portions of the cup lid with a condiment holder that form no part of the claimed design. The dot-dash broken lines depict a boundary of the claimed design. The long dash-long dash lines represent sectional view planes and form no part of the claimed design.

1 Claim, 6 Drawing Sheets
